UNITED STATES PATENT OFFICE

172,547

WHEEL TRIM OR SIMILAR ARTICLE

George Albert Lyon, Detroit, Mich.

Application June 11, 1953, Serial No. 25,445

Term of patent 14 years

(Cl. D14—30)

To all whom it may concern:

Be it known that I, George Albert Lyon, a citizen of the United States and a resident of the city of Detroit, in the county of Wayne and State of Michigan, have invented a new, original, and ornamental Design for a Wheel Trim or Similar Article, of which the following is a specification, reference being had to the accompanying drawing, forming a part thereof.

On the drawing:

Figure 1 is a side elevational view of a wheel trim, showing my new design;

Figure 2 is a profile view showing the cross sectional contour of the wheel trim of Figure 1; and

Figure 3 is a fragmentary side perspective view of the wheel trim.

The dotted lines in Figures 1 and 2 showing the conventional tire and wheel assembly are for illustrative purposes only.

I claim:

The ornamental design for a wheel trim or similar article, substantially as shown and described.
